UNITED STATES PATENT OFFICE.

CHARLES MCLEOD, OF TORONTO, ONTARIO, CANADA, ASSIGNOR TO MASSEY-HARRIS COMPANY, LIMITED, OF TORONTO, CANADA.

ADJUSTABLE TONGUE.

1,113,458.

Specification of Letters Patent. Patented Oct. 13, 1914.

Application filed February 28, 1913. Serial No. 751,323.

To all whom it may concern:

Be it known that I, CHARLES MCLEOD, of the city of Toronto, in the Province of Ontario, Canada, have invented certain new and useful Improvements in Adjustable Tongues, of which the following is a specification.

This invention relates to tongues which are adapted to be adjusted to any desired angle and which are therefore particularly adapted for use with agricultural implements which are to be connected in gangs to be drawn by a traction engine, and my object is to devise a simple and strong construction of the supporting base on which the tongue is pivoted and with which the adjusting mechanism is connected. I attain this object by means of the construction hereinafter described and illustrated in the accompanying drawings.

Figure 1 is a side elevation of the adjustable tongue connected with the frame of the binder. Fig. 2 is a plan view of the same. Fig. 3 is a face view of the spiral hoop gear by means of which the adjustment of the tongue is effected.

In drawing like numerals of reference indicate corresponding parts in the different figures.

In this invention three main parts are concerned; a supporting base adapted to be secured to a binder frame, a tongue pivotally supported thereon and adjusting means between the tongue and the supporting base.

The supporting base is substantially the same as that disclosed in the co-pending application, Ser. No. 751,324, of Walter A. Watts, and comprises essentially the braces 1 and 2 connected together at their forward ends to form a triangle. The rearward ends of these members are adapted for connection with a binder frame, the former in a manner to be hereinafter described and the latter by being provided with a hook 3 adapted to engage in the eye 4 suitably formed on or connected with the binder frame. This specific arrangement whereby the member 2 may rock in a vertical plane may, however, be constructionally departed from without departing from the spirit of my invention.

A member 5 forming a transverse tongue support is secured at one end to the member 1 at the apex of the triangle formed by the members 1 and 2. The other end of the member 5 forming the tongue support has a

rearwardly extending brace member 6 secured thereto, the rear end of this brace member 6 extending rearwardly to a point adjacent the rear end of the member 1. Between the rear ends of the braces 1 and 6 is secured a block 7 which serves as a pivot for the tongue 8. Rearwardly of the block 7 the ends of the braces 1 and 6 are brought close together to embrace the bracket 9 formed on or secured to the frame of the binder and the bolt 10 extending through the ends of the members 1 and 6 and the bracket 9 forms a horizontal pivot on which the members 1 and 6 may rock in a vertical direction.

The forward part of the tongue 8 is preferably formed of wood while the rearward end is formed of two metal straps 11 which embrace the tongue support 5 and the block 7. The latter is provided with the trunnions 12 on which the straps 11 are pivoted, as shown particularly in Fig. 1. Suitable cotter pins 13 are passed through the trunnions to retain the straps 11 in position thereon. The tongue may thus swing freely from side to side being supported by the member 5.

The adjustment of the tongue is effected by means of a rack 14 carried by the supporting base and a spiral gear 15 carried by the tongue. The rack 14 is preferably formed of malleable cast iron and is shaped as the arc of a circle, the center of which is the pivot of the adjustable tongue. The teeth of the rack face rearwardly and its ends are suitably bolted to the members 1 and 6 of the supporting base. The hoop gear 15 is secured to the spindle 16 journaled in a bearing bracket 17 secured to the tongue.

For the purpose of actuating the spindle 17 I provide the inclined spindle 18 connected with the spindle 16 by means of the universal joint 19. The spindle 18 is also provided with the universal joint 20 which enables its rear end to be laid at any desired angle to any convenient place from which it may be operated preferably beside the seat of the operator in charge of the binder, a crank handle 21 providing means whereby the spindle may be actuated.

The supports for the spindle 18 on the binder must, of course, be such as will permit of the spindle adjusting itself to the position of the supporting frame of the adjustable tongue as the latter is swung up or down.

The method of vertically adjusting the supporting base, however, forms no part of the present invention and will not be described in detail. In Fig. 1 one of the links 22 to 5 which power may be applied to raise and lower the supporting base is partly shown.

From the above description it will be seen that by rotating the spiral slip gear 15 the tongue may be swung to any desired position 10 within the scope of the rack 14. The arrangement described for adjusting the tongue is very strong and simple and has the advantage that all joints in the adjusting mechanism are eliminated the only flexibility called for being in the operating spindle for adjusting mechanism.

What I claim as my invention is:—

1. In mechanism of the class described the combination with a supporting base comprising two members, each adapted at its rear end for connection with the apparatus to be drawn and secured together at their forward ends to form a triangle, and a transverse member forming a tongue support 25 connected at one end with the two former members at the apex of the triangle, and a rearwardly extending brace member connecting the other end of the tongue support with the member on which the tongue is 30 pivoted adjacent said pivot, of a tongue pivoted on one of said first mentioned members adjacent to its rear end; a curved rack rigidly supported on the aforesaid members, and means carried by the tongue and engaging the rack whereby the angle of the tongue 35 may be adjusted.

2. In mechanism of the class described a

supporting base formed of three external members arranged in rhomboidal form in plan and a diagonal member connecting opposite angles of the rhomboid, a pivotal connection for a tongue being formed adjacent one obtuse angle, and a connection for tongue-adjusting mechanism adjacent the other obtuse angle, the side of the rhomboid 45 opposite the pivotal connection for the tongue being provided with a curved rack.

3. In mechanism of the class described the combination with a supporting base formed of three external members arranged in rhomboidal form in plan and a diagonal member connecting opposite angles of the rhomboid, a vertical pivotal connection for a tongue being formed near the rear of the base and also two horizontal pivotal connections whereby the base may be connected with the apparatus to be drawn, the side of the rhomboid opposite the pivotal connection for the tongue being formed with a 50 curved rack.

4. In mechanism of the class described the combination of a tongue supporting base, a curved rack rigidly supported on said base and facing rearwardly and upwardly; a tongue pivoted on said base behind the rack, 55 and a spiral hoop gear carried by the tongue and engaging the rack whereby the angle of the tongue may be adjusted.

Toronto, this 11 day of Jan., 1913.

CHARLES McLEOD.
